[57] CLAIM

The ornamental design for a housing for a telephone
instrument, as shown.

DESCRIPTION

FIG. 1 is a perspective view of a housing for a tele-
phone instrument.

FIG. 2 is a perspective view of the housing for a tele-
phone instrument seen from below and one side.

FIG. 3 is a perspective view of the housing for a tele-
phone instrument seen from the side opposite the side
shown in FIG. 2.

FIG. 4 is a perspective rear view of the housing for a
telephone instrument.

FIG. 1

FIG. 3

FIG. 4
